UNITED STATES PATENT OFFICE.

EMMETT JOHN SLATER, OF DETROIT, MICHIGAN, ASSIGNOR TO AMERICAN BLOWER COMPANY, OF DETROIT, MICHIGAN, A CORPORATION OF NEW YORK.

FAN HOUSING OR CASING.

Application filed October 15, 1918. Serial No. 258,263.

To all whom it may concern:

Be it known that I, EMMETT J. SLATER, a citizen of the United States, residing at Detroit, in the county of Wayne and State 5 of Michigan, have invented certain new and useful Improvements in Fan Housings or Casings, of which the following is a specification, reference being had therein to the accompanying drawing.

10 This invention relates to housings for fans, pumps, distributors and the like, and method of forming the same.

For many years it has been the general practice in the art to which the present invention relates to form fan housings or casings of a casting, usually cast iron, and since in many instances these housings must be rather small, they are hard to cast, easily become broken, and the expense of making 15 the same is considerable.

It has also been suggested to form housings of sheet steel or other suitable sheet metal, but when so constructed the housings have been made up of a plurality of 20 sections, the usual form being to divide the housings in the middle, at substantially right angles to the axis, and either secured together as by bolts, rivets and the like or else soldered or welded at the point of connection between the sections. This type of 25 construction is also more or less expensive and is open to other and further objections in that the seam or joint oftentimes is found to leak, and under vibration the sections become disjoined, when subjected to the usual strain in usage.

It is therefore the primary object of the present invention to overcome recognized disadvantages and objections incident to the 30 formation and use of fan housings as constructed and used at the present time, the improvements including reduction in the cost of production and upkeep, simplicity in design, greater efficiency in use and increased strength and durability.

In carrying out the invention it is proposed to construct a housing or casing for fans of sheet metal, preferably from a single sheet, such as steel, iron, aluminum, 35 brass or any other suitable material, with the result that the body portion of the housing proper will be devoid of peripheral or side joints, and present a substantially continuous unbroken interior and exterior 45 surface.

The improvements are of importance not only because of the smooth and finished appearance of the housing, but because the sheet metal construction provided and the method of forming the same makes possible 60 a perfect cut-off where the scroll joins the outlet connection, and such perfect cut-off cannot be obtained by any of the usual forms of construction heretofore tried out wherein the casings have been made of sheet 65 metal.

The invention further includes a novel construction and formation of sheet metal blank formed of yieldable material whereby the same may be bent, stretched, or rolled 70 into the desired shape to form the housing, with means whereby when the ends of the sheet are joined a complete housing including the scroll and outlet results.

Still other improvements, in the construction, and novel method of forming the same will be appreciated from the description to follow which for a clear understanding of the invention is to be considered in connection with the accompanying drawings, 80 forming a part hereof, and wherein is disclosed, for the purpose of illustration a convenient and satisfactory embodiment of the invention as well as the various steps in carrying out the method.

85 Referring to the drawings:

Figure 1 is a perspective view of a fan housing made in accordance with the invention;

Figure 2 is a plan of an original sheet 90 metal blank to be formed into a housing;

Figure 3 is an end view of the same;

Figure 4 illustrates the blank partially rolled whereby to form the side flanges;

Figure 5 is an end view of the same;

Figure 6 illustrates the form of the blank after having been subjected to a further rolling operation;

Figure 7 is a view of the blank after the lateral projections or wings have been closed 100 or contacted with one another to form the housing outlet;

Figure 8 illustrates the blank with the scroll slightly kinked or bent;

Figure 9 illustrates the blank in its completed rolled or bent condition with the side wings of one end of the scroll overlying the wall of the outlet.

With reference to the drawings, as will be appreciated from an inspection of Fig-

ure 1 more particularly, the casing or housing comprises a body or scroll part 1 substantially cylindrical throughout the main portion thereof and connecting with a tangential extension 2. The body portion is provided with side flanges 3 which gradually increase in width circumferentially in a direction towards the connection of said flanges with the base or outlet portion of 10 the housing. The tangential extension 2 is curved upon itself to form a tubular outlet 4 and the flanges 3 have suitable ears or lugs 5 adapted to overlie the wall of the tubular outlet 4, and being secured thereto 15 as by rivets 6, welding or any other means of connection. When the ears or lugs 5 are secured in place on the tubular outlet part, the tubular formation of the outlet is reinforced and will be maintained in closed 20 position at the joint of its parts, and the scroll will at the same time be maintained in its proper form and shape.

The housing or casing is conveniently made up of a blank substantially as illustrated in Figure 2 of the drawings, and preferably of sheet metal such as steel. The blank comprises a body part A having tapering sides B which at the enlarged end curve outwardly at C and merge into lateral lugs or 25 extensions D. At the opposite reduced end of the blank the sides have an inwardly curved part E connecting with outwardly projecting tongues or lugs F connecting with one another at the end of the blank by a terminal segmental cut-out part G.

It is obvious of course that the blank is of yieldable material whereby the same may be bent, rolled, stretched, etc., by the action of suitable machines or tools employed for 40 this purpose, and not necessary to illustrate herein.

In the formation of the housing for the blank the first operation consists in rolling the blank up into a substantially U-shape 45 as illustrated in Figures 4 and 5. Thereupon the blank is placed in a suitable machine or operated upon by suitable tools which still further rolls the blank into the form illustrated in Figure 6. Thereupon 50 either by the same machine or tools, or other machines or tools the lateral extensions are closed whereby to form the tubular outlet 4 of the casing. The scroll part of the housing is thereupon slightly bent or kinked at 55 the top as illustrated in Figure 8, when the machine or tools are employed to swing the smaller ears or tongues F into the position illustrated in Figure 9 in flat position overlying the sides of the tubular outlet 4. Thereupon the tongues F (being illustrated 60 at 5 in Figure 1) are secured in place as by rivets 6, and the complete housing or casing is thereby formed. The curved portion G of the blank corresponds with the curvature of the tubular outlet 4 and makes a

snug fit with the upper edge thereof which it overlies.

It has been ascertained that a casing or housing made in accordance with the present invention while exceedingly simple in design and neat in appearance, is exceedingly strong and durable in use, and the expense over prior constructions is considerably decreased. In making articles of this character the labor question is also an item of 75 considerable importance, and it has been ascertained that whereas before one man could only make a few dozen of these housings in a day when the same were constructed of cast iron, when made of sheet steel as contemplated herein, they can be produced by hundreds of thousands per day with approximately the same cost for labor. It is to be borne in mind that the present construction of casing or housing may be successfully employed for centrifugal pumps, 80 vacuum cleaners, dust separators, cream separators, etc.

What I claim is:

1. In a housing or casing for fans and the like, the combination of a tubular outlet part formed of sheet metal, the wall of said tubular outlet part having an integral extension bent and curved to form a scroll and means for securing the free end of the scroll 95 to the wall of the outlet part whereby to complete the housing.

2. In a housing or casing for fans and the like, the combination of a tubular outlet part formed of sheet metal, the wall of said tubular outlet part having an integral extension curved to form a scroll and secured at its free end to the wall of the outlet part whereby to complete the housing, certain parts of 100 said free end of the extension overlying the 105 sides of the outlet part whereby to reinforce the same.

3. A sheet metal casing or housing for fans and the like, comprising a curved body part forming an open scroll, and an integral 110 extension on the body part forming a closed tubular outlet tangentially disposed with respect to the body part, the tubular outlet and body part having overlapping portions secured one to the other.

4. A casing or housing for fans and the like, comprising a single-piece of sheet metal, curved longitudinally and transversely upon itself to form an open body part or scroll and a closed tangential tubular outlet projecting beyond the scroll, the sides of the scroll at the free end thereof overlying the 115 sides of the tangential outlet and secured to the latter whereby to maintain the joint between the parts of the outlet closed.

5. A casing or housing for fans and the like, formed from sheet metal, and comprising a curved body part, with open sides and integral flanges overlying the openings at the sides, the body part being curved upon 120 125 130

itself and united whereby to form a scroll, and the said body part having an integral extension which is closed, whereby to form a tangential tubular outlet.

5 6. In a casing or housing for fans and the like formed of sheet metal, the combination of a tubular outlet part and a connected body part curved upon itself to form a scroll with one or more open sides, one end 10 of the body part having a curved cut-out part to conform to the configuration of the tubular outlet, and having projecting parts overlying and secured to the outlet part.

7. A casing or housing for fans and the like, the combination of a tubular outlet part, a scroll part integral therewith, parts of the scroll part overlying the sides of the outlet part and secured to the latter, the outlet part being tangentially disposed with 20 respect to the scroll part.

8. A casing or housing for fans and the like, comprising an outlet and scroll part formed of sheet metal bent upon itself and united, the scroll part being substantially 25 continuous and unbroken, the peripheral wall of the outlet being closed throughout and the said outlet constituting an integral tangential extension of the scroll part.

9. A sheet metal blank for forming casings or housings for fans and the like comprising an elongated body part having at 30 one end lateral extensions adapted to be folded into contact at the edges whereby to form a tubular outlet, and said blank having at its opposite end lateral projections of less width than their said lateral extensions at the opposite end whereby to engage over the tubular outlet when the blank is curved to form a substantially cylindrical open scroll 35 in communication with said outlet with the latter tangentially disposed with regard to the scroll.

10. A blank for forming casings or housings for fans and the like of sheet metal comprising an elongated sheet having a substantially straight edge at one end connecting with lateral extensions, and a segmental edge at its opposite end connecting with lateral extensions of less width than 45 the first named lateral extensions, said lateral connections merging at the sides into the sides of the blank, and said sides tapering inwardly towards one another in a direction towards the lateral extensions of 50 less width.

55 11. A blank for forming casings or housings for fans and the like of sheet metal comprising an elongated sheet having a substantially straight edge at one end connecting with lateral extensions, and a segmental edge at its opposite end connected with lateral extensions, said lateral connections merging at the sides into the sides of the blank, and the sides of the blank between 60 the end extensions being tapered.

12. The method of forming sheet metal housings or casings for fans and the like which consists in forming an elongated sheet of metal with lateral projections at opposite ends, bending the projections at one end to 70 form an outlet part, curving the body part of the blank to form a substantially cylindrical body part of the housing, and connecting the projections at the opposite ends of the blank to the body part of the blank 75 at its point of connection with the outlet part of the housing.

13. The method of forming sheet metal housings for fans or the like, which consists in forming an elongated sheet metal blank 80 with lateral projections at one end and a segmental recess at its opposite end, curving the body portion of the blank to form a substantially cylindrical part, and bending said lateral extensions to form a tubular outlet, with the segmental end of the cylindrical part overlying the tubular outlet, and securing said segmental end in place.

14. The method of forming housings or casings for fans and the like of sheet metal 90 which consists in forming an elongated blank with a straight rear edge and a segmental forward edge, the straight rear edge connecting with lateral extensions, and the segmental forward edge connecting with 95 lateral extensions of the blank, bending the blank into substantially U-shape, connecting the sides of the rear lateral extensions to form a tubular outlet, curving the body portion of the U-shape blank whereby the segmental end overlies the tubular outlet part, and connecting the lateral projections at the inner end to the sides of the tubular outlet part.

15. The method of forming casings for 100 fans and the like of sheet metal which consists in forming an elongated blank with a substantially straight rear edge and a segmental forward edge the rear edge connecting with relatively wide lateral extensions, 110 and the segmental forward edge connecting with lateral extensions, the sides of the blank tapering inwardly from the wide lateral extensions in a direction toward the extensions at the opposite end, bending the 115 blank into substantially U-shape, connecting the sides of the relatively wide lateral extensions to form a tubular outlet, curving the body portion of the U-shaped blank whereby the segmental end overlies the tubular outlet part, and connecting the lateral extensions at the forward edge of the blank to the sides of the tubular outlet part.

120 In testimony whereof I hereunto affix my signature in the presence of two witnesses.
